CLAIM

The ornamental design for laptop computer, as shown and described.

DESCRIPTION

FIG. 1 is a front perspective view of a laptop computer in accordance with our new and ornamental design;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom plan view thereof.

The ports, the holes around the perimeter of the bottom surface, and the regions within the center bottom surface shown in broken lines in FIGS. 1-5 and 7 represent portions of the laptop computer and form no part of the claimed design.

1 Claim, 5 Drawing Sheets
